R. S. BLAIR

RAILWAY SIGNALING

Filed April 5, 1924

UNITED STATES PATENT OFFICE.

ROBERT S. BLAIR, OF STAMFORD, CONNECTICUT.

RAILWAY SIGNALING.

Application filed April 5, 1924. Serial No. 704,370.

This invention relates to railway signaling and more particularly to railway signaling as applied to protection against the dangers of a roadway blocked by a stalled train or 5 otherwise obstructed.

One of the objects of the invention is to provide a signaling means of the above nature practical and efficient and capable of meeting the requirements of practical use in 10 a highly satisfactory manner. Another object is to provide means of the above nature dependable in operation. Another object is to provide signaling means capable of effectively warning an approaching train of the 15 existence of a blocked track. Other objects are to provide such means of inexpensive construction and simple to operate. Another object is to provide an effective art of railway signaling whereby the hazards due to a 20 stalled train or other obstruction are substantially reduced. Other objects will be in part obvious or in part pointed out hereinafter.

The invention accordingly consists in the features of construction, combinations of elements, arrangements of parts and in the several steps and relation and order of each of the same to one or more of the others all as will be illustratively described herein, and the scope of the application of which will be 30 indicated in the following claims.

In the accompanying drawing in which are shown one or more various possible embodiments of the several mechanical features of this invention,

35 Figure 1 is a side elevation of a signaling device in operative position.

Figure 2 is a section taken substantially along the line 2—2 of Figure 1.

Figure 3 is a section taken substantially 40 along the line 3—3 of Figure 1.

Figure 4 is a top plan view of the signaling device.

Figure 5 is a rear elevation showing certain parts in another position of adjustment, 45 and

Figure 6 diagrammatically represents the signaling device in operation upon a curved railway track.

Similar reference characters refer to similar parts throughout the several views of the drawing.

Referring now to the drawing in detail, there is shown a railway rail 10 upon which this signaling device is adapted to be mounted. The device is preferably supported upon

the rail 10 by means of a pair of wheels coacting with the rail and is adapted to be driven or propelled along the rail by suitable means such as will presently be described. The forward wheel is shown in section in Figure 3 and may comprise, for example, a solid roller 11 which is of some yielding or easily compressible material such as cork. The roller 11 rests upon the surface of the rail 10, and passing axially therethrough is a pin 12 which holds in place a pair of side disks 13 and 14. These disks 13 and 14 are dished outwardly, as shown, and serve as side flanges for the wheel, being adapted to engage the sides of the rail 10 to guide the wheel along the rail. The pin 12 is of light construction and is provided with a head 12^a at one end and removable securing means such as a cotter pin 15 at the other end, whereby the disks 13 and 14 are conveniently removable. The disks 13 and 14 are of light construction being, for example, of thin sheet metal and may, if desired, be made of a stiff paper or cardboard. These disks or side flanges are further preferably perforated, as shown, to lessen the wind resistance thereof. If the disks 13 and 14 are made of paper or cardboard, they are preferably waterproofed.

The rear wheel, as shown in section in Figure 2, may comprise a pair of spaced circular disks 16 and 17 connected by an axial pin 18 and provided with peripheral flanges 16^a and 17^a which rest upon the surface of the rail 10. This wheel also is provided with dished flanges 19 and 20 adapted to coact with the sides of the rail and taking the form, for example, of cup-shaped members resting against the outer faces of the respective disks 16 and 17. The pin 18 is of light construction holding the flanges 19 and 20 against the disks 16 and 17 and provided with a head 18^a at one end and a removable securing device, such as a cotter pin 21, at the other end whereby the flanges 19 and 20 may be conveniently removed, if desired. The disks 16 and 17 and the flanges 19 and 20 are of light construction, being formed, for example, from thin sheet metal, and as mentioned with respect to the flanges 13 and 14 of the front wheel, the flanges 19 and 20, may be made, if desired, of waterproofed paper or cardboard. These flanges 19 and 20 are also preferably perforated to lessen their wind resistance.

The axial pins 12 and 18 of the two wheels are connected together by means of a suit-

able frame, taking the form, for example, of a pair of longitudinal connecting members 22 and 23, through the ends of which the pins 12 and 18 loosely pass. These connecting members 22 and 23 are preferably strips of light sheet metal.

As shown in Figure 4, the forward ends of the members 22 and 23 are supported upon the pin 12 at either side of the wheel member 11, and rearwardly thereof they are preferably bent inwardly toward each other. At this point just in back of the forward wheel, the frame members 22 and 23 support a device which is adapted to provide a visible signal taking the form preferably of a red light. The burning charge of this red light may be contained in a cylindrical cardboard container 24 which is clamped, as shown in Figure 4 by the frame members 22 and 23, and a pair of small rivets 25 and 26 passing through the two frame members. The container 24, if of cardboard, is preferably waterproofed, and, as shown in Figure 1, is supported as near the surface of the rail 10 as practicable to keep low the center of gravity of the device, thereby increasing its stability. The burning charge of the red light, if desired, may be coiled or doubled back within its container 24.

This signaling device is adapted to be driven along the rail 10 by driving means carried thereon and preferably taking the form of a rocket. It will be understood that the term "rocket" as employed herein is to be interpreted in a broad sense to comprehend a suitable burning device adapted, by the reaction due to the discharge of its burning gases, to propel the device upon which it is mounted. The rocket employed in this invention comprises preferably a long tube 27 of small diameter containing the burning charge of the rocket. The charge is preferably of the slow burning type so that the propulsion effect is gradual, being preferably not all expended in one initial blast. The rocket tube 27 may be of cardboard and is preferably waterproofed.

As shown in Figure 1, the rocket tube 27 is preferably suspended beneath the frame members 22 and 23 in order that the weight thereof may be carried near the surface of the rail 10. The forward end thereof is supported and securely clamped by a light bracket 28 secured to the frame members 22 and 23 by the rivet 26. The rear end of the tube 27 projects beyond the rear wheel and beyond the rearmost portions of the flanges 19 and 20. As shown in Figure 2, the rear end of the rocket tube 27 is supported from the pin 18 preferably by means of a depending loop 29 which may be of wire or a strip of thin sheet metal. The loop 29 is formed with bends therein to provide a surplus of length so that the position of the rear end of the rocket tube may be adjusted upwardly or

downwardly or to either side to vary the direction of discharge of the rocket with respect to the longitudinal center line of the device. Spacing collars 30 and 31 of cork, if desired, may be employed about the pin 18 between the frame members 22 and 23 and the supporting loop 29.

The device is driven along the rail 10 by the reaction due to the discharge of the preferably slow burning rocket 27. By means of the adjustable support 29, the rear end of the rocket may be raised, if desired, so that the reaction is forwardly and downwardly tending to hold the device against the surface of the rail. Furthermore, if found desirable for any reason, by means of the same adjustment the reaction may be made upwardly inclined to tend to lift the forward end of the device. In order to further lessen wind resistance, there is provided forwardly of the front wheel, a prow-shaped shield 32 which is also preferably inclined downwardly to tend to hold the device against the rail. This wind shield 32 is preferably made of light sheet metal and may be supported by means of a pair of brackets 33 and 34 rigidly connected to the frame members 22 and 23 by the rivet 25 and passing upwardly over the wheel member 11. The wind shield 32, if employed, preferably does not project upwardly to a sufficient height to interfere with a view of the red light 24 from the front of the device. There are shown secured to the frame members 22 and 23, a pair of outwardly and downwardly projecting wings 35 and 36 which are preferably of light sheet metal and may be conveniently bent and adjusted as desired. These wings 35 and 36 are adapted to serve as wind vanes and may be adjusted to have any desired degree of effect in assisting to hold the device against the rail. These wind vanes 35 and 36 and the wind shield 32, although preferably employed, may be dispensed with if found unnecessary.

The fuse 27^a of the rocket 27 by means of which the charge of the rocket is ignited to start the movement of the device along the rail, is preferably protected by a shield 37 which may be of waterproofed paper. As the device is propelled along the rail the burning of the charge within the rocket tube 27 progresses from the fuse 27^a forwardly through the rocket tube. The nature of the rocket charge is preferably such that the rocket burns with a red discharge. Communicating with the interior of the tube 27 is a fuse 38 connected at its other end with the charge of the red light 24. When the burning of the rocket charge reaches the fuse 38, the latter is ignited and immediately ignites the red light. By properly positioning the point at which the fuse 38 enters the rocket tube 27, the point in the travel of the device at which the red light is lighted, may be adjusted and determined. Thus the red light may be ig-

nited when the device has reached the end of its travel or at any intermediate point between the starting and stopping of such travel. The fuse 38 is preferably provided with a water-
5 proof covering 39 to protect the same from moisture and insure dependable operation.

As shown at 42 there may be mounted on the under side of the thin member 32 an ordinary torpedo 43 which will thus travel 10 along continuously in operative relation to the rail and give an audible signal should a train be met.

This signaling device is particularly adapted for the protection of the rear of a stalled 15 train. When a train stops, as between stations, this device may be sent back along the track from the rear of the train and its burning red light serves to effectively warn an approaching train of the blocked condition of 20 the track. The rocket may be made so that its charge is sufficient to propel the device along the track for substantially the required distance, whereupon the device coming to rest remains upon the rail and the red light continues 25 to burn as an effective danger signal. This obviates the necessity of sending back a flagman and the delay in starting occasioned by the necessity of waiting for the flagman to return. The entire device is compressible 30 in the sense that it may be run over by a train and compressed against the rail or knocked therefrom without danger of derailing the train. It may therefore be left upon the rail with perfect safety, the rocket charge and the 35 red light charge being burned out. The charge of the red light may be made such that it will burn for any desired length of time.

When the device is sent back along a curved 40 track, it is preferably placed upon the rail at the outside of the curve, as illustrated in Figure 6. In this instance the suspension 29 of the rocket tube 27 may be adjusted so that the discharge of the rocket is substantially in 45 the direction indicated by the arrow 41 in Figure 6. The reaction from the discharge driving the device along the rail thus serves also to tend to urge the flanges of the wheels against the inner side of the curved rail to aid in holding the device thereon.

In Figure 5, there is illustrated a section through a rail when snow or cinders or gravel are filled up around the rail. In such case, the flanged wheels of the train passing over 55 the rail clear the material away from the inner side of the rail, as indicated at 42, but the obstruction at the outer side of the rail remains intact, as indicated at 43, after the passage of the car wheels thereover. The outer 60 flanges of the wheels of the signaling device must therefore be removed since the obstructing material 43 would interfere with their operation. In this Figure 5, there is shown a rear elevation of the device with the flange 20 65 of the rear wheel removed, it being under-

stood that the corresponding flange 13 of the forward wheel is also removed. When this is done, the suspension 29 of the rocket tube 27 is adjusted in the manner shown in Figure 5, so that the reaction of the burning rocket 70 urges the remaining flanges 19 and 14 against the side of the rail to hold the device upon the rail. Thus, regardless of the obstruction, at the outer side of the rail, the signaling device may be made to dependably travel along 75 the surface of the rail.

From the above it will be seen that there are herein provided an art of railway signaling and an apparatus therefor which attain the objects of this invention and produce 80 many important practical advantages.

As many possible embodiments may be made of the mechanical features of the above invention and as the art herein described might be varied in various parts all without 85 departing from the scope of the invention, it is to be understood that all matter herein set forth or shown in the accompanying drawings is to be interpreted as illustrative and not in a limiting sense. 90

I claim as my invention:

1. The herein described art of railway signaling, which consists in mounting a signaling device on the top and inner side of a rail and applying thereto forces directed 95 along the rail and outwardly toward the rail to cause it to travel along the same with an outward tendency.

2. The herein described art of railway signaling, which consists in directing a rocket- 100 driven signal along a railway rail and varying the direction of discharge of said rocket with respect to said rail.

3. The herein described art of railway signaling, which consists in directing a rocket- 105 driven signaling device along a railway rail and adjusting wind vanes on said signaling device to hold the same on said rail.

4. In a railway signal, in combination, a signaling device adapted to travel along a 110 rail substantially free from engagement with the outside of the rail and having a portion adapted to engage the inside of the rail, and means mounted on said device adapted to apply forces to said device urging it along the 115 rail and outwardly toward the rail.

5. In a railway signal, in combination, a signaling device adapted to travel along a rail substantially free from engagement with the outside of the rail and having a portion 120 adapted to engage the inside of the rail, and a rocket mounted on said device in a position to drive the same along said rail with a component outwardly toward the rail.

6. In a railway signal, in combination, a 125 signaling device having a member adapted to roll along a rail and a pair of removable flaring flanges adapted respectively to engage the sides of the rail and guide the device, and means adapted to propel the device along the 130

rail, said device being adapted to travel along said rail in engagement with the top and one side only.

7. In a railway signal, in combination, a flanged wheel adapted to travel along a single rail, supporting means mounted on said wheel and adapted to follow the same with said wheel in engagement with the rail, a rearwardly discharging rocket mounted on said supporting means, and a signal mounted on said supporting means.

8. In a railway signal, in combination, a flanged wheel adapted to travel along a single rail, supporting means mounted on said wheel and adapted to follow the same with said wheel in engagement with the rail, a rearwardly discharging rocket mounted on said supporting means, and a signal mounted on said supporting means, the flanges of said wheel being of open construction to reduce the wind resistance thereon.

9. In a railway signal, in combination, a flanged wheel adapted to roll along a single rail, supporting means connected with said wheel to follow the same, a pair of spaced wheel members connected with said supporting means, and a rocket mounted upon said supporting means and discharging rearwardly between said last wheel members.

10. The herein described art of railway signaling which consists in mounting a signaling device on the top and inner side of a rail and discharging therefrom burning gases in a rearward and inward direction to force said device outward toward the rail and propel it along the rail.

11. The herein described art of railway signaling which consists in mounting a signaling device on a rail, driving it along the rail by the reaction of rearwardly discharged burning gases, and utilizing the air resistance to the movement of said device to force it in a predetermined direction with respect to said rail.

12. In a railway signal, in combination, a support, means comprising a wheel carrying the forward end of said support, a pair of wheels carrying the rear end of said support and spaced one from another, a rocket mounted upon said support and adapted to dis-

charge between the wheels of said pair and propel the device along the rail, and rotary means adapted to hold said device against outward displacement with respect to said rail.

13. In a railway signal, in combination, a support, a roller at the forward end of said support adapted to extend entirely across the face of the rail, a pair of spaced wheels at the rear end of said support, and a rocket mounted on said device to extend between and to discharge between the wheels of said pair and propel the device along the rail.

14. In a railway signal, in combination, a rocket, means comprising flanged wheels adapted to permit said rocket to travel along a rail and hold it in predetermined position with respect thereto, and a combustible signal device associated with said rocket and adapted to be carried therewith.

15. In a railway signal, in combination, a rocket, means comprising flanged wheels adapted to permit said rocket to travel along a rail and hold it in predetermined position with respect thereto, and a combustible signal device associated with said rocket and adapted to be carried therewith, the flanges of said wheels being open to reduce the wind effect thereon.

16. In a railway signal, in combination, a rocket, means mounting said rocket to permit it to travel along a rail by its reaction when burning, and a pair of rotary members one of which is in advance of the other and both of which are adapted to engage the same side of the head of the rail and each of which is inclined in a radial direction away from the central plane of the rail.

17. In a railway signal, in combination, a signal device adapted to travel along a rail comprising a rocket adapted to discharge rearwardly, a rotary means for supporting the rocket on the rail, and a member at the forward end of the device adapted to utilize its air resistance in tending to exert a force upon the device in a predetermined direction.

In testimony whereof, I have signed my name to this specification this 3rd day of April, 1924.

ROBERT S. BLAIR.
